(57) **CLAIM**

The ornamental design for a potato piece, as shown.

DESCRIPTION

FIG. 1 is a perspective view of a potato piece embodying the new design;
 FIG. 2 is a front elevational view thereof;
 FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The evenly-spaced broken lines in FIGS. 1–7 illustrate end portions of the potato piece that form no part of the claimed design. The dash-dot-dash broken lines in FIGS. 1 and 4–7 illustrate the boundary of the claimed design which forms no part thereof.
